UNITED STATES PATENT OFFICE.

STEPHAN BROICHGANS, OF MILWAUKEE, WISCONSIN.

LAWN-SPRINKLER.

SPECIFICATION forming part of Letters Patent No. 469,023, dated February 16, 1892.

Application filed September 17, 1891. Serial No. 405,939. (No model.)

To all whom it may concern:

Be it known that I, STEPHAN BROICHGANS, a citizen of the United States, and a resident of Milwaukee, in the county of Milwaukee, 5 and in the State of Wisconsin, have invented certain new and useful Improvements in Lawn-Sprinklers; and I do hereby declare that the following is a full, clear, and exact description thereof.

10 The object of my invention is to provide a lawn-sprinkler having chambers for the accumulation of sand and other sediment which would otherwise clog the sprinkler and choke or wholly prevent the flow of water; and it 15 also has for its object to provide such a sprinkler that will economize the water and effect a better distribution of the same than is ordinarily the case, and to also arrange the parts as to prevent unnecessary wear.

20 My invention therefore consists in certain peculiarities of construction and arrangement of parts to be hereinafter described, with reference to the accompanying drawings, and subsequently claimed.

25 In the drawings, Figure 1 represents a side elevation of my device, partly in vertical transverse section and partly broken away for the purpose of better illustration; and Fig. 2, a plan view, partly in horizontal section.

30 Referring by letter to the drawings, A represents a preferably globular sediment-chamber mounted upon legs B and provided with right-angular extensions C, D, the latter one of these extensions being screw-threaded or 35 otherwise detachably secured to the lower end of a vertical pipe E, said pipe having its upper end likewise secured to the lower end of a hollow stud F, the latter being practically a continuation of said pipe E and may, if 40 found desirable, be integral therewith.

The upper portion of the hollow stud F is reduced somewhat to form an annular shoulder a, that serves as a rest for the lower end of a thimble G, loosely fitted over said hollow stud, and to properly hold the thimble G in place and at the same time prevent water and sediment from lodging between said thimble and stud I provide a packing b' and check-nuts c' c², said packing being arranged intermediate of the upper edge of said thimble and the check-nut c², both of said nuts being

screwed to the upper end of the aforesaid hollow stud.

The lower end of the thimble G is provided with an exteriorly-screw-threaded offset b, 55 having an outwardly-extending annular flange c, and engaging the screw-threaded offset b, and impinging against the flange c is the lower interiorly-screw-threaded portion of a chamber H, the latter being preferably cylindrical 60 in shape at the bottom and spherical at the top.

From the foregoing construction and arrangement of parts it will be seen that I provide a circular space d intermediate of the 65 thimble G and lower cylindrical portion of the chamber H for a purpose to be hereinafter described.

I represents sprinkler-tubes having the usual curvature, the inner ends of said tubes 70 engaging screw-threaded openings e in the upper part of the cylindrical portion of the chamber H and the outer ends being provided with caps f, having slots g. Extending through and secured to the top of the spherical portion of chamber H is another sprinkler-tube 75 h, the lower end of the latter being provided with openings i and the upper end with a cap j, similar to the caps f, at the outer ends of the 80 sprinkler-tubes I.

Assuming that the parts are in the position shown in Fig. 1, with the chamber-extension C connected to a hose or pipe fitted to a source of water-supply, and it is desired to operate my device, the water when turned on will run 85 into the lower chamber A up through the vertical pipe E into the upper chamber H, through the sprinkler-tubes I h, and be finally discharged in the form of spray through the cap-slots at the ends of said sprinkler-tubes, the 90 force of the water revolving the thimble G, together with the upper chamber H and sprinkler-tubes I h upon the hollow stud F.

By providing the slotted caps at the ends of the sprinkler-tubes I obtain a better distribution of the water, although the latter result depends somewhat upon the vertical sprinkler-tube h, which not only serves as an outlet for water, but also as an inlet for air, the latter rising to the top of the chamber H 100 and serving as an additional pressure for the water.

It will be observed that by providing the lower chamber A and the space *d* intermediate of the thimble G and lower cylindrical portion of the chamber H sand and other sediment in the water will accumulate therein and prevent the sprinkler from being clogged, thereby doing away with the difficulty heretofore experienced.

Having thus described my invention, what I claim as new, and desire to secure by Letters Patent, is—

1. In a lawn -sprinkler, the combination, with a suitably-mounted base forming a sediment-chamber free from pipes or other obstructions and having inlet and outlet in the walls thereof, of a pipe rising from said outlet, a hollow stud secured to the upper end of said pipe, a suitably-packed revoluble thimble mounted on said hollow stud, a tight air, water, and sediment chamber secured to said thimble, spraying-tubes projecting laterally from the walls of said tight chamber, and a vertical air-inlet and spraying-tube projecting within said tight chamber and extending above it, substantially as shown and described.

2. In a lawn -sprinkler, the combination, with a suitably-mounted base forming an unobstructed sediment-chamber having proper inlet and outlet, a pipe rising therefrom, a hollow plug secured to said pipe, and a revoluble thimble mounted on said hollow plug, of a tight air, water, and sediment chamber secured to said thimble, spraying-pipes extend-

ing laterally from the walls of said tight chamber, and a vertical air-inlet and spraying-tube projecting within said tight chamber and having a closed bottom and a series of openings above the same within said chamber, and spraying-caps on the outer ends of said spraying pipes and tube, substantially as shown and described.

3. In a lawn -sprinkler, the combination, with a revoluble thimble mounted on the upper end of the water-passage pipe, of a tight air, water, and sediment chamber secured to said thimble, a series of imperforate pipes extending laterally from the walls of said chamber, caps on the outer ends of said pipes, having transverse slots across their vertical outer faces, and a vertical tube projecting within said tight chamber and extending above the same, the lower end of said tube being closed and having perforations just above said closed end and the upper outer portion of said tube being imperforate and fitted with a cap at its end having a transverse slot across its horizontal upper face, substantially as shown and described.

In testimony that I claim the foregoing I have hereunto set my hand, at Milwaukee, in the county of Milwaukee and State of Wisconsin, in the presence of two witnesses.

STEPHAN BROICHGANS.
